(57) **CLAIM**

The ornamental design for a case for portable electronic computing device, as shown and described.

DESCRIPTION

FIG. 1 is a top perspective view of a case for portable electronic computing device showing our new design.

FIG. 2 is a rear elevational view thereof.

FIG. 3 is a front elevational view thereof.

FIG. 4 is a right elevational view thereof.

FIG. 5 is a left elevational view thereof.

FIG. 6 is a top plan view thereof; and,

FIG. 7 is a bottom plan view thereof.

The broken lines in the figures illustrate portions of the case for portable electronic computing device that form no part of the claimed design.
